To all whom it may concern:

Be it known that I, Frank Rushforth, a citizen of the United States, and a resident of the city of Los Angeles, in the county of Los Angeles and State of California, have invented a new, original, and ornamental Design for a Holder for Tissue Dispenser, of which the following is a specification, reference being had to the accompanying drawing, forming a part thereof, in which:

Figure 1 is a perspective view of the holder taken from the front and showing my new design;

Fig. 2 is a front view of the holder;

Fig. 3 is a rear view of the holder; and

Fig. 4 is an end view thereof.

The suction cup and bumper disclosed by means of phantom lines in Fig. 4 are shown only for purposes of illustration.

I claim:

The ornamental design for a holder for tissue dispenser, substantially as shown.
